[57] ABSTRACT

An assembly for converting a handgun to a rifle wherein an elongated rifle barrel having locking means thereon which is identical to the locking means on the handgun barrel is substituted within the handgun in place of the conventional short handgun barrel. The handgrip cover plates are removed from the handgun and the handgun with the rifle barrel inserted therein is placed between a pair of handgrip engaging plates which form a portion of a rifle stock. The handgrip cover plates are placed on the outer faces of the handgrip engaging plates and a pair of securing members are inserted through aligned apertures in the handgrip cover plates, the handgrip engaging plates and the handgrip to secure the handgun within the rifle stock. A handrest stock member extends forwardly of the handgrip engaging plates and is secured to one of the plates by means of a connecting member having a cutout portion which permits access to the trigger when in the assembled condition. A rod-like member extends rearwardly of and is secured to a U-shaped connecting member which is formed integrally with the handgrip engaging plates. A shoulder plate is secured to the terminal end of the rod-like member.

HANDGUN TO RIFLE CONVERSION ASSEMBLY**BACKGROUND OF THE INVENTION**

This invention relates generally to firearms and more particularly to an assembly for converting a handgun to a rifle.

The basic structural and functional characteristics of a handgun and a rifle are extremely diverse, and where one type of firearm is completely satisfactory for a particular purpose, the other may not be suitable at all. It is therefore often desirable, although not entirely practical, to have both a handgun and a rifle accessible at the same time such that the person utilizing the firearms may choose that firearm which is most suitable for the purpose. Carrying a separate handgun and rifle is not always a practical solution to the problem, since the weight, bulk and expense of two separate firearms creates additional problems. It has, therefore, become increasingly desirable to have a single firearm which may be converted from a handgun to a rifle without substantially increasing the weight, bulk, or expense of the firearm. Assemblies for converting a handgun into a rifle have been utilized in the past, and although acceptable for many purposes, such devices have not been wholly satisfactory in that they are difficult to assemble, require many different parts, substantially increase the weight of the handgun, have been generally bulky in nature, and are relatively expensive. Further, in order to sell a handgun to rifle conversion kit without compliance with recent gun legislation, means must be provided for precluding the use of the handgun in a rifle assembly with its conventional short barrel.

SUMMARY OF THE INVENTION

Accordingly, an object of the present invention is to provide a new and improved assembly for converting a handgun to a rifle which is inexpensive to manufacture, durable in structure, relatively lightweight, and easy to install.

Another object of this invention is to provide an assembly for converting a handgun to a rifle which utilizes all of the components of the handgun with the exception of the barrel.

A further object of the instant invention is to provide an assembly for converting a handgun to a rifle which is relatively easy to install without the use of special tools or implements.

A further object of the invention is to provide an assembly for converting a .45 caliber semi-automatic handgun to a rifle which includes means for preventing the use of the handgun without placing a barrel of sufficient length to qualify as a rifle therein.

A still further object of the instant invention is to provide an assembly for converting a .45 caliber semi-automatic handgun to a rifle which is easy to convert, inexpensive to manufacture, well balanced, and relatively lightweight.

Briefly, in accordance with one illustrative embodiment of this invention, the foregoing and other objects are obtained by providing an assembly for converting a handgun to a rifle wherein the handgun is of conventional design having a relatively short removable barrel with locking means thereon and removable handgrip cover plates, the assembly having a rifle barrel of substantially greater length than the relatively short removable barrel of the handgun, wherein the rifle bar-

rel has locking means identical in size and shape to the handgun barrel locking means for receipt within the handgun, and a rifle stock for supporting the handgun and the rifle barrel with the rifle barrel locked within the handgun in place of the relatively short barrel.

Many other advantages and objects of the present invention will become readily apparent as the following detailed description of the invention unfolds when taken in conjunction with the accompanying drawings.

BRIEF DESCRIPTION OF THE DRAWING

FIG. 1 is an exploded perspective view of the handgun and conversion assembly; and

FIG. 2 is a perspective view of the handgun assembled as a rifle.

DESCRIPTION OF THE ILLUSTRATIVE EMBODIMENT

Referring now to the drawing, wherein like reference characters designate identical or corresponding parts throughout the several views, and more particularly to FIG. 1, whereon a conventional .45 caliber semi-automatic handgun is indicated generally by the numeral 10, with a pair of handgrip cover plates 12 removed therefrom. When assembling the handgun 10 as a rifle, the conventional barrel is removed therefrom and an elongated rifle barrel 14 is substituted within the handgun 10 in place thereof. The barrel 14 has a locking means such as swivel lug 16 and grooves 18 which are of the same size and shape as the locking means utilized on the conventional .45 caliber semi-automatic handgun barrel.

The handgun 10 with the rifle barrel 14 installed therein and the handgrip cover plates 12 removed therefrom, is placed between a pair of handgrip engaging plates 20 and 22. A generally U-shaped member 24 is formed integrally with plates 20 and 22 so as to interconnect the lower rearward portions thereof for holding the plates 20 and 22 in a spaced parallel relationship a distance substantially equal to the thickness of the handgrip 26 of the handgun. Each of the plates 20 and 22 has a pair of apertures 28 therein which are of the same size and in alignment with the conventional apertures 30 in the handgrip 26 and the apertures 32 in the handgrip cover plates 12. With the handgrip 26 between handgrip engaging plates 20 and 22, and with handgrip cover plates 12 on the outer faces of plates 20 and 22, the apertures 28, 30 and 32 are aligned such that conventional securing members such as screws may be inserted therethrough for securing the handgun 10 within the rifle stock member.

A generally U-shaped handgrip stock member 34 is provided forwardly of the handgrip engaging plates 20 and 22 so as to provide support for rifle barrel 14 within a groove 35 and to further provide a handgrip for the rifle assembly. Handgrip 34 is secured to a plate-like member 36 by conventional securing means such as screws 38. The member 36 is formed integrally with plate member 20 extending forwardly therefrom, and has a cutout portion 39 on the lower portion thereof for providing access to the trigger 40 and trigger guard 42 of the handgun 10.

A safety mechanism 100 is provided at the rearmost end of the groove 35 in the handgrip stock member 34 for precluding the use of the handgun 10 without the

barrel 14 having a length greater than the barrel normally associated with the handgun 10. The safety mechanism 100 comprises a formed spring steel member having an upwardly stepped portion 101 formed therein and a locking extension 102 projecting rearwardly therefrom as shown in FIG. 1. The locking extension 102 is of such length that when the handgun 10 is slipped forwardly into position in the stock member, the locking extension 102 will cause the conventional cocking assembly C of the handgun 10 to be moved rearwardly by engaging the lower most portion of the forward end of the cocking assembly C. This prevents the handgun 10 from being fired with the short barrel since the cocking assembly C will not go far enough forward to allow the hammer of the handgun 10 to operate. On the other hand, when the barrel 14 having a length greater than the conventional barrel of the handgun 10 is placed therein and it is positioned in a stock member 34, the barrel 14 engaged the stepped portion 101 in the safety mechanism 100 and causes the stop extension 102 to be deflected downwardly so that it will not engage the forward end of the cocking assembly C. Therefore, when someone attempts to use a short barrel in the handgun 10 with the invention, it cannot be operated, but when someone uses the longer barrel 14 therein, it will operate in the manner set forth herein.

Extending rearwardly from the U-shaped connecting member 24 is a rod-like member 44 which is secured thereto by conventional means such as welding. On the rearward terminal portion of rod member 44 is a shoulder rest plate 46 secured thereto by conventional means such as welding. Rod 44 could be hinged to member 24 to provide a folding assembly if so desired.

As shown in the assembled position in FIG. 2, the rifle assembly provides a lightweight well-balanced device which is easily assembled and relatively inexpensive to manufacture. The basic components of the .45 caliber semi-automatic handgun have not been substantially altered, in that only the barrel has been replaced by a barrel of similar construction and extended length and the handgrip covers have been removed from the handgun and installed on the stock assembly.

It will be obvious to those skilled in the art that many variations may be made in the embodiment chosen for the purpose of illustrating the present invention, without departing from the scope thereof, as defined by the appended claims.

What is claimed as invention:

1. An assembly for converting a handgun to a rifle wherein said handgun is of conventional design having a handgrip and a relatively short removable barrel with a locking means thereon and removable handgrip cover plates, said assembly comprising:

a rifle barrel of substantially greater length than said relatively short removable barrel of said handgun, said rifle barrel having locking means thereon for receipt within said handgun wherein said rifle barrel locking means is identical in size and shape to said handgun barrel locking means, and

a rifle stock for supporting said handgun and said rifle barrel with said rifle barrel locked within said handgun in place of said relatively short barrel, said rifle stock comprising a pair of substantially

parallel handgrip engaging plates spaced a distance substantially equal to the width of said handgrip when said cover plates are removed therefrom, a generally U-shaped member formed integrally with and extending rearwardly of said handgrip engaging plates,

an elongated rod secured to and extending rearwardly of the apex of said generally U-shaped member, a shoulder rest plate secured to the rearward terminal portion of said elongated rod, a hand rest stock member for supporting a portion of said rifle barrel, and means for securing said hand rest stock member to at least one of said handgrip engaging plates.

2. An assembly for converting a handgun to a rifle according to claim 1 wherein:

said handgrip engaging plates are generally conforming in shape to said handgrip cover plates, apertures in said handgrip engaging plates and aligned apertures in said handgrip and cover plates whereby said handgun is secured to said rifle stock by inserting said handgrip between said engaging plates with said cover plates on the outer surfaces of said engaging plates and providing securing members through said aligned apertures.

3. An assembly for converting a handgun to a rifle according to claim 2 wherein said means for securing said handrest stock member to at least one of said handgrip engaging plates comprises a relatively flat member formed integrally with said handgrip engaging plate and having a portion defined thereon for providing access to the trigger of said handgun when in assembled condition.

4. An assembly for converting a handgun to a rifle according to claim 3 wherein said handgun is a conventional .45 caliber semi-automatic pistol.

5. An assembly for converting a handgun to a rifle wherein said handgun is of conventional design having a relatively short removable barrel with a locking means thereon and removable handgrip cover plates, said assembly comprising:

a rifle barrel of substantially greater length than said relatively short barrel of said handgun, said rifle barrel having locking means thereon for receipt within said handgun wherein said rifle barrel locking means is identical in size and shape to said handgun barrel locking means, and

a rifle stock for supporting said handgun and said rifle barrel with said rifle barrel locked within said handgun in place of said relatively short barrel, said assembly further including means for precluding the firing of said handgun when positioned in said assembly when said barrel has a length substantially equal to that of the relatively short removable barrel normally associated with said handgun, said means being constructed and arranged to be rendered inoperative when said barrel has a length substantially greater than the relatively short removable barrel normally associated with said handgun.

6. An assembly for converting a handgun to a rifle wherein said handgun includes a cocking device and has a relatively short removable barrel with a locking means thereon and wherein a rifle barrel substantially

longer than said first mentioned barrel is provided, said rifle barrel having a locking means and adapted to be received in the handgun in place of said first mentioned barrel, said assembly comprising means for precluding firing of said handgun, including a resilient member having a stepped portion and a locking extension, said locking extension constructed and arranged to engage said cocking device in its normal position and displac-

5 ing said cocking device from its forwardmost firing position for precluding the firing of said handgun, and said stepped portion constructed and arranged to be engaged by said rifle barrel for moving said locking extension out of engagement with said cocking device to permit firing of said handgun.
